United States Patent Office

Des. 220,588
Patented Apr. 27, 1971

220,588

LIFTING BODY

William T. Holmes, Lancaster, Calif., assignor to the United States of America as represented by the Administrator of the National Aeronautics and Space Administration

Filed Feb. 4, 1970, Ser. No. 21,263

Term of patent 14 years

Int. Cl. D12—07
U.S. Cl. D71—1

FIG. 1 is a top plan view of the lifting body showing the new design.

FIG. 2 is a side elevational view of the lifting body of the design.

FIG. 3 is a bottom plan view thereof.

FIG. 4 is an end elevational view thereof.

FIG. 5 is an opposite end elevational view thereof.

FIG. 6 is a perspective view of the new design.

I claim:

The ornamental design for a lifting body, substantially as shown.
